UNITED STATES PATENT OFFICE.

ADOLF MOUREK, OF RATHBUN, IOWA.

LOCK.

1,081,133.

Specification of Letters Patent.

Patented Dec. 9, 1913.

Application filed September 18, 1912. Serial No. 789,664.

To all whom it may concern:

Be it known that I, ADOLF MOUREK, a citizen of the United States, residing at Rathbun, in the county of Appanoose and 5 State of Iowa, have invented certain new and useful Improvements in Locks, of which the following is a specification.

This invention relates to door-locks having a plurality of tumblers which are engageable with a sliding bolt, and its object 10 is to provide a novel arrangement of tumblers to be hereinafter described and claimed.

The invention also has for its object to 15 provide a lock which is devoid of complicated parts liable to get out of order, and also to provide a lock which is strong and durable, and which can be cheaply manufactured.

20 In the accompanying drawing forming a part of this specification, Figure 1 is an inside face view of the lock. Fig. 2 is an edge view thereof, and Fig. 3 is a vertical section on the line 3—3 of Fig. 1.

25 Referring specifically to the drawing the lock casing is a flat block 5 rectangular in shape, or otherwise shaped. The block is adapted to be mounted on the door and secured thereto by screws or other suitable 30 fastenings 6, the top and bottom portions of the block having perforations for this purpose.

The inner face of the block 5 has a series 35 of vertical slots or ways 7 in each of which is slidably mounted a tumbler, the latter comprising a flat bar 8 of a depth and width to fit in the slot. The tumbler is reduced in width at its lower end, leaving a shoulder 9 and a depending finger 10, the back 40 edge of which latter, at its outer end has a recess 11 which forms a shoulder 12. Adjacent to the lower ends of the slots 7 are shoulders 12^a which are engageable by the shoulders 12.

45 In that face of the block 5 having the slots 7 is a transverse passage 13 which intersects the lower ends of said slots. The depth of this passage is less than the depth of the slots. In the passage 13 is mounted a sliding bolt 14 having in its top edge a number 50 of notches 15 corresponding to the number of tumblers 8. When the notches 15 are in alinement with the slots 7, the tumblers 8 drop into the notches. The shouldered portions of the tumblers enter the notches, the reduced portions or fingers 10 lying behind

the bolt in those portions of the slots which are back of the passage.

The bottom wall of the passage 13 is undercut as indicated at 16, forming a key-hole which crosses the lower ends of the slots 7. The bottom wall also has a longitudinal recess 17 into which extends a lug or stud 18 carried by the bottom edge of the bolt 14, to limit the travel of the latter and prevent its entire withdrawal from the passage 13.

60 The key for operating the tumblers 8 comprises a stem 19 having a number of bits 20 corresponding to the number of tumblers 70 and spaced apart a distance corresponding to the spacing of the tumblers.

The rear end of the bolt 14 projects a sufficient distance from the housing 5 so that it may be advanced or retracted by hand.

75 The tumblers drop down by gravity and enter the notches 15 to lock the bolt when said notches come in line with the slots 7. In this position of the tumblers, the fingers 10 thereof are spaced a short distance from 80 the lower ends of the slots. Thus, when the key is inserted into the key-hole 16, and adjusted to place the bits 20 close to the ends of the fingers 10, and then turned in the proper direction, the bits push against 85 the ends of the fingers and the tumblers are raised to retract the portions which seat in the notches 15, thereby releasing the bolt, and allowing the latter to be advanced or retracted. The bolt can be reversed to project from either side of the casing 5.

90 A lock constructed as herein described is strong, durable and efficient, it is entirely devoid of complicated parts liable to get out of order, and in view of the small number 95 of parts employed it can be very cheaply manufactured.

I claim:

1. A lock comprising a casing having a plurality of slots, and a passage intersecting one end of the slots, said passage having an undercut portion forming a key-hole which crosses the last-mentioned ends of the slots, a bolt slidable in the passage and having notches, and tumblers slidably mounted in the slots and having shouldered portions entering the notches of the bolt when said notches are in alinement with the slots, said tumblers having reduced portions extending from the shoulders and lying in 105 the slots back of the bolt and terminating adjacent to the key-hole.

2. A lock comprising a casing having a plurality of slots, and a passage intersecting one end of the slots, said passage having an undercut portion forming a key-hole 5 which crosses the last-mentioned ends of the slots, a bolt slideable in the passage and having notches, said bolt projecting from opposite sides of the housing and being reversible, and tumblers slidably mounted in the 10 slots and having shouldered portions entering the notches of the bolt when said notches are in alinement with the slots, said tumblers having reduced portions extending from the shoulders and lying in the slots 15 back of the bolt and terminating adjacent to the key-hole.

3. A lock comprising a casing having a plurality of slots, and a passage intersecting one end of the slots, said passage hav-

ing an undercut portion forming a key-hole 20 which crosses the last-mentioned ends of the slots, a bolt slideable in the passage and having notches, and tumblers slidably mounted in the slots and having shouldered portions entering the notches of the bolt 25 when said notches are in alinement with the slots, said tumblers having reduced portions extending from the shoulders and lying in that portion of the slots which is intersected by the passage, and spaced from the ends of 30 said slots which are crossed by the key-hole.

In testimony whereof I affix my signature in presence of two witnesses.

ADOLF MOUREK.
